US00D586818S

(12) **United States Design Patent**
Luck

(10) **Patent No.:** **US D586,818 S**
(b4) **Date of Patent:** **** Feb. 17, 2009**

(54) **COMPUTER DISPLAY WITH CUSTOMER
SPECIFIC TRANSPORT NETWORK
PERFORMANCE USER INTERFACE**

(75) Inventor: **Richard Wayne Luck**, Kenmore, WA
(US)

(73) Assignee: **Telecom Transport Management, Inc.**,
Seattle, WA (US)

(**) Term: **14 Years**

(21) Appl. No.: **29/276,770**

(22) Filed: **Feb. 5, 2007**

(51) **LOC (9) Cl.** **32-00**

(52) **U.S. Cl.** **D14/485**

(58) **Field of Classification Search** **D14/485,**

(57) **CLAIM**

The ornamental design for a computer display with customer specific transport network performance user interface, as shown and described.

DESCRIPTION

The sole FIGURE is a front view of a computer display with a customer specific transport network performance user interface.

The outer rectangle shown in broken line is a portion of a computer display included for the purpose of illustrating environmental structure and forms no part of the claimed design. The text shown in broken line forms no part of the claimed design.
